(57) CLAIM

The ornamental design for an electric fan with clamp, as shown and described.

DESCRIPTION

FIG. 1 is an exploded front, right side and top perspective view of an electric fan with clamp showing my new design; FIG. 2 is a front elevational view of the fan shown separately for clarity of illustration;

FIG. 3 is a rear elevational view of FIG. 2;

FIG. 4 is a right side elevational view of FIG. 2;

FIG. 5 is a left side elevational view of FIG. 2;

FIG. 6 is a top plan view of FIG. 2;

FIG. 7 is a bottom plan view of FIG. 2;

FIG. 8 is a front elevational view of the clamp shown separately for clarity of illustration;

FIG. 9 is a rear elevational view of FIG. 8;

FIG. 10 is a right side elevational view of FIG. 8;

FIG. 11 is a left side elevational view of FIG. 8;

FIG. 12 is a top plan view of FIG. 8; and,

FIG. 13 is a bottom plan view of FIG. 8.
